VACUUM CLEANER DISPLAY DEVICE

Arthur L. McCarthy, Detroit, Mich., assignor to
 Eureka Vacuum Cleaner Company, Detroit,
 Mich., a corporation of Michigan

Application October 3, 1938, Serial No. 233,070

12 Claims. (Cl. 35—13)

This invention relates generally to display equipment and refers more particularly to a device for illustrating the operation of suction or vacuum cleaners.

5 It is one of the principal objects of this invention to provide a relatively simple display device for visually illustrating the action of a suction cleaner in performing the cleaning function on a surface covering.

10 Another advantageous feature of this invention resides in the provision of a display device rendering it possible to visually illustrate the action of the agitating means associated with the suction nozzle of many vacuum cleaners.

15 Still another object of this invention consists in providing the display device with means engageable with the handle supporting trunnions at opposite sides of the vacuum cleaner casing to support the cleaner in a position where the 20 action thereof on a surface covering may be clearly viewed.

25 A further feature of the present invention consists in providing a display device which is not only compact and attractive in appearance, but which may be readily transported as a unit from one point to another for demonstration purposes.

The foregoing, as well as other objects, will be made more apparent as this description proceeds, especially when considered in connection with 30 the accompanying drawings, wherein:

35 Figure 1 is a perspective view of a display device forming the subject matter of this invention and illustrating the vacuum cleaner in broken lines;

Figure 2 is a front elevational view of the 40 display device showing the vacuum cleaner in one position of adjustment on said device;

Figure 3 is a perspective view of the display device illustrating the vacuum cleaner in another 45 adjusted position of the device;

Figure 4 is a detailed sectional view taken substantially on the plane indicated by the line 4—4 of Figure 2;

Figure 5 is a sectional view taken substantially 45 on the plane indicated by the line 5—5 of Figure 3;

Figure 6 is a wiring diagram of the electrical connections employed in the display device.

Although my improved display device is not 50 limited in its use to any particular type of suction cleaner, nevertheless, for the purpose of illustrating the present invention, I have selected a suction cleaner of the following design. In general, the suction cleaner is shown in the 55 several views as comprising a nozzle 10 having

the usual relatively narrow elongated mouth 11 normally located adjacent the surface covering to be cleaned and communicating with the air intake opening of a suitable blower 12 in accordance with the usual practice. The discharge 5 side of the blower 12 communicates with the dirt receiving bag or receptacle 13 in a manner such that the dirt drawn through the mouth 11 of the nozzle is discharged by the blower 12 into the receptacle 13.

10 The fan (not shown) of the blower is driven by a suitable electric motor supported in the housing 14 and operatively connected to a revoluble brush 15 supported in the mouth 11 of the nozzle 10. The particular driving connection between the motor and brush 15 is not shown herein, since it forms no part of the present invention and may be of the well known type. The brush 15 is also of conventional design in that it is provided with two rows of bristles 16 extending in a spiral from opposite ends of the brush and adapted to contact with the 20 surface covering.

25 Referring now more particularly to the display device, it will be noted that this device is adapted to support the suction cleaner briefly described above in either of the two positions shown in Figures 2 and 3. Upon reference to Figure 1, it will be noted that the display device comprises a supporting base 17 having a pair 30 of brackets 18 and 19 secured thereto in lateral spaced relationship. The space between the brackets is slightly greater than the width of the motor housing 14 on the suction cleaner to provide for inserting this housing between the upper 35 extremities of the brackets with the handle supporting trunnions 20 extending into openings 21 provided in the brackets at their upper ends. Upon reference to Figure 5, it will be noted that the manner in which the trunnions 20 are connected to the brackets is identical to the method employed in connecting the usual handle (not shown) to the suction cleaner. In detail, the upper ends of the brackets are supported on the trunnions 20 between washers 22 and are secured in assembled relation to the trunnions by means of screws 23 threaded in the outer ends of the trunnions.

40 Also mounted upon the support 17 is a standard 50 having provision for displaying suitable advertising or descriptive matter. In detail, the standard 55 comprises a pair of stanchions 26 in the form of tubes secured to the support 17 at opposite sides of the brackets by means of couplings 27 and adapted to slidably receive suitable pins 55

28 depending from the bottom side of a frame 29. The frame 29 is fashioned to support a plate 30 on which the descriptive matter or advertising is placed, and a lamp 31 is secured to the top bar 32 of the frame in a position to illuminate the advertising matter on the plate 30.

5 For the purpose of controlling the operation of the electric motor in the housing 14 of the suction cleaner, a switch assembly 33 is mounted on the support 17 in a convenient position. The 10 assembly 33 comprises a toggle switch 34 corresponding to the conventional switch usually supported on the handle of the suction cleaner in that it has three positions of adjustment. When the 15 switch operating lever 35 is in its lowermost position shown in Figure 1, the motor is running at a relatively low speed and when this lever is in its uppermost position, the motor operates at a relatively high speed. On the other hand, 20 when the switch operating lever 35 is moved to a position intermediate the two above extreme positions, the supply of electrical energy to the motor is discontinued.

The switch assembly 33 also comprises three 25 electrical outlets, designated in the diagram shown in Figure 6 by the reference characters 36, 37 and 38. The electrical contacts of the outlet 36 are connected to the corresponding contacts of the outlet 37 through the medium of the switch 30 34, while the electrical contacts of the outlet 38 are directly electrically connected to the corresponding contacts of the outlet 37. The outlet 36 at the top of the assembly 33 is shown in Figure 1 as adapted to detachably engage a plug 39 35 which, in turn, is electrically connected to the suction cleaner motor supported in the housing 14. The outlet 37, on the other hand, is adapted to detachably receive a plug 40 connected to a suitable source of electrical energy through the 40 medium of the conductor 41, with the result that the suction cleaner motor is adapted to be electrically connected to the source of supply through the switch 34. The outlet 38 at the bottom of the assembly 33 is shown in Figure 1 as adapted 45 to detachably receive a plug 42 electrically connected to the lamp 31 through the medium of the conductor 43.

The suction cleaner is adapted to be supported 50 between the brackets 18 and 19 in the inverted position thereof so that the mouth 11 of the nozzle 10 is clearly visible. When the suction cleaner is in the position thereof shown in Figures 1 and 2, the top wall of the cleaner rests on the support 17 and the mouth 11 of the nozzle 10 is 55 inclined with respect to the vertical in a rearward direction, or in a direction toward the brackets 18 and 19. The angle of inclination of the mouth 11 of the nozzle is predetermined to permit a strip of surface covering A to rest 60 against the mouth 11 in the manner clearly shown in Figure 1. The surface covering employed for the purpose of demonstration has an area sufficient to completely cover the mouth 11 of the nozzle when supported in the position thereof 65 shown in Figure 1, so that when the switch 34 is moved to either of its operative positions to start the motor in the housing 14 of the cleaner, the suction created by the fan will draw the surface covering against the mouth 11 of the nozzle.

70 As pointed out above, the motor in the housing 14 of the cleaner is also connected to the brush 15 for rotating the latter, and this brush is so adjusted with respect to the mouth 11 of the nozzle that the bristles 16 project beyond the 75 plane of the mouth 11 so as to contact with the

adjacent side of the surface covering. Inasmuch as the two rows of bristles 16 on the brush extend spirally of the brush, it follows that the surface covering is fed, or moved upwardly relative to the nozzle to simulate the movement of the suction cleaner over the surface covering during normal operation. This upward movement of the surface covering continues until the lower edge of the surface covering is advanced beyond the lower edge portion of the mouth 11 of the 1 nozzle 10, whereupon the interior of the nozzle is open to the atmosphere and the suction or vacuum pull is destroyed. When this condition exists, the surface covering slides downwardly relative to the mouth of the nozzle under the action of 1 gravity until the mouth 11 is again sealed and the vacuum pull re-established on the surface covering. This cycle of operation continues as long as the suction cleaner is in operation, and the 2 repeated oscillation of the surface covering relative to the nozzle is highly advantageous from the 21 standpoint of attracting attention.

When demonstrating the action of the cleaner on rugs or carpets, the strip of sample carpet is positioned with the warp or back against the 22 mouth 11 of the nozzle so that the pile is visible. As the bristles of the brush engage the warp of the surface covering to raise the latter upwardly relative to the nozzle 10, these bristles impart a vibratory movement to the surface covering which 30 has the effect of loosening or jarring the powder or granular material, previously rubbed into the pile of the rug, to such an extent that this material is actually discharged from the pile of the rug into the pan 45 mounted on the support 17 in a 35 position to receive the material as it drops from the rug. It should be understood that this demonstration is effected with a surface covering having a weave of such a texture that it prevents any appreciable amount of air from being drawn 40 through the rug by the action of the suction on the back of the rug.

The pan 45 is held against shifting movement 45 relative to the support 17 by means of dowels 46' depending from the bottom of the pan and engageable in recesses formed in the support 17. In the present instance, the dowels have upwardly projecting extensions 47' positioned to engage the lower edge of the strip of rug A in the event the latter tends to slide away from the nozzle as 50 it drops by gravity relative to the nozzle 10.

In the action of the inverted suction cleaner, there is a tendency for the spirally arranged bristles on the brush to shift the surface covering longitudinally of the nozzle and, in order to prevent this shifting movement, I provide a pair 55 of guides 50 extending transversely of the pan adjacent opposite ends of the latter and having a sliding engagement with opposite sides of the pan to permit adjusting the same toward and 60 away from each other. In the specific embodiment of the invention, the guides are in the form of inverted U-shaped clips having spring metal leg portions 51 fashioned to snap into engagement with the bead 52 formed on the upper 65 edge of the pan. As a result of this construction, any tendency for the surface covering to shift longitudinally of the nozzle and destroy the vacuum pull on the surface covering is prevented.

It will also be observed from Figures 1 to 3, 70 inclusive, that each of the guides 50 is provided with a lateral extension 54 in the form of a bar secured to the base portions of the inverted U-shaped guides and extending to a position at the front side of the surface covering. The free ends 75

of the guides are shown as bent downwardly in a manner to cooperate with the extensions 47' to guide the surface covering during the interval the latter drops by gravity.

In the event it is desired to demonstrate the action of the suction, as well as the vibratory action of the bristles, a strip of carpet is selected having a weave sufficiently loose to permit the powdered substance to be drawn through the nozzle into the bag 13. When conducting such a demonstration, the bag 13 is preferably disconnected from the discharge side of the blower so that the powdered substance drawn through the rug will be visible.

In the event it is merely desired to demonstrate the strength of the suction of the cleaner, the latter is preferably swung to the position thereof shown in Figure 3 wherein the mouth of the nozzle 10 is disposed horizontally. The suction cleaner is held in this position by means of a stud 46 threaded in the bracket 18 and having a reduced portion 47 adapted to extend into a recess formed in the adjacent side of the housing 14 on the cleaner. In this position of the suction cleaner, the brush 15 is preferably disconnected from the motor and a strip of floor covering is placed over the top of the mouth 11 of the nozzle. Prior to placing the strip of covering material over the nozzle 10, a powdered substance is preferably rubbed over the nap and the receptacle 13 is disconnected from the discharge side of the blower so that the substance previously applied to the carpet will be visible as it is discharged from the blower. Also, in the horizontal position of the suction cleaner shown in Figure 3, a plate, such as a board B may be placed over the mouth 11 of the suction nozzle and the strength of the suction is demonstrated by requesting the interested party to remove the board from the nozzle. The force required to lift the board from the nozzle will, of course, vary in dependence upon the strength of the suction and will serve to effectively demonstrate the efficiency of the cleaner.

Thus, from the foregoing, it will be observed that I have provided a relatively simple display device rendering it possible to demonstrate the action of a vacuum cleaner in a unique manner which will attract considerable attention. It will also be noted that my improved display device is compact in construction and may be readily transported from one point to another for demonstration purposes.

What I claim as my invention is:

1. In a suction cleaner display device, a suction cleaner having a nozzle, a support in the form of a platform, means on the platform for supporting the suction cleaner in an inverted position with the nozzle disposed at an angle to the platform, a strip of surface covering resting against the nozzle opening and having an area sufficient to cover said opening, suction means embodied in the cleaner effective to draw the strip of surface covering against the nozzle opening, and means in the nozzle and engageable with the strip of surface covering to impart a vibratory movement to the strip.

2. In a suction cleaner display device, a suction cleaner having a nozzle, a support in the form of a platform, means on the platform for supporting the suction cleaner in an inverted position with the plane of the nozzle opening extending at an angle to the platform, a strip of surface covering resting against the nozzle opening and having an area sufficient to cover said opening,

suction means embodied in the cleaner effective to draw the strip of surface covering against the nozzle opening, and revoluble means in the nozzle having a portion engageable with the adjacent side of the strip of surface covering and effective to advance the strip relative to the nozzle.

3. In a suction cleaner display device, a suction cleaner having a nozzle and having driving means, a support in the form of a platform, means on the platform for supporting the suction cleaner in an inverted position with the nozzle arranged at an angle to the platform, a strip of surface covering resting against the nozzle and having an area sufficient to cover the nozzle opening, suction means embodied in the cleaner and driven by the driving means to draw the strip of surface covering against the nozzle opening, and means driven by said driving means and effective to raise the strip of surface covering relative to the nozzle until the lower edge of the surface covering uncovers a portion of the nozzle to destroy the action of the suction and thereby permit the surface covering to drop by gravity to a position wherein the same again seals the nozzle to re-establish the vacuum pull on the strip.

4. In a suction cleaner display device, a suction cleaner having a nozzle and having driving means, a support in the form of a platform, means on the platform for supporting the suction cleaner in a position with the nozzle facing upwardly and inclined with respect to the platform, a strip of surface covering resting against the nozzle opening and having an area sufficient to cover said opening, suction means embodied in the cleaner and driven by the driving means to draw the strip of surface covering against the nozzle opening, a member rotatably supported in the nozzle and driven by said driving means, and bristles extending from the rotatable member beyond the nozzle opening to engage the adjacent side of the surface covering and raise the surface covering relative to the nozzle.

5. In a suction cleaner display device, a suction cleaner having a nozzle and having driving mechanism, a support in the form of a platform, means on the platform for supporting the suction cleaner in a position with the nozzle facing upwardly and inclined with respect to the platform, a strip of surface covering against the nozzle opening and having an area sufficient to cover said opening, suction means embodied in the cleaner and driven by the driving mechanism to draw the strip of surface covering against the nozzle opening, means in the nozzle and driven by the driving means to impart a vibratory movement to the strip of surface covering, and a receptacle carried by the platform in a position to receive the foreign matter discharged from the surface covering by the vibratory movement thereof.

6. In a suction cleaner display device, a suction cleaner having a nozzle and having an electrically operated driving mechanism, a support in the form of a platform, means on the platform for supporting the suction cleaner in a position with the nozzle facing upwardly and inclined with respect to the platform, a strip of surface covering resting against the nozzle opening and having an area sufficient to cover said opening, suction means embodied in the cleaner and driven by the electrical driving mechanism to draw the strip of surface covering against the nozzle opening, means in the nozzle and driven by the electrical driving mechanism to impart a vibratory move-

- ment to the strip of surface covering, and a unit secured to the platform having a switch and having provision for electrically connecting the driving mechanism to a source of electrical supply through said switch.
7. In a suction cleaner display device, a suction cleaner having a nozzle and having an electrically operated driving mechanism, a support in the form of a platform, means on the platform for supporting the suction cleaner in a position with the nozzle facing upwardly and inclined with respect to the platform, a strip of surface covering resting against the nozzle opening and having an area sufficient to cover said opening, suction means embodied in the cleaner and driven by the electrical driving mechanism to draw the strip of surface covering against the nozzle opening, and means supported in the nozzle and driven by the driving mechanism including a brush having bristles engageable with the adjacent side of the surface covering to raise the latter relative to the nozzle and to impart a vibratory movement to the strip of surface covering.
8. In a suction display device, a suction cleaner having a nozzle, a support in the form of a platform, means on the platform for supporting the suction cleaner in a position with the nozzle facing upwardly and inclined with respect to the platform, a strip of surface covering resting against the nozzle and having an area sufficient to cover the nozzle opening, suction means embodied in the cleaner and effective to draw the strip of surface covering against the nozzle opening, releasable means located in the nozzle and engageable with the adjacent side of the surface covering to raise the surface covering relative to the nozzle until the lower edge of the surface covering uncovers a portion of the nozzle to destroy the action of the suction and thereby permit the surface covering to drop by gravity, and means carried by the platform and engageable with the surface covering as the latter drops by gravity relative to the nozzle to guide the same.
9. In a device for displaying the action of a suction cleaner having a nozzle, a support in the form of a platform, means on the platform for supporting the suction cleaner in a position with the nozzle of the cleaner facing upwardly and inclined with respect to the platform, a strip of surface covering resting against the nozzle, and means also carried by the platform and engageable with opposite ends of the surface covering to prevent lengthwise shifting movement of the surface covering relative to the nozzle.
10. In a device for displaying the action of a suction cleaner having a nozzle, a support in the form of a platform, means on the platform for supporting the suction cleaner in a position with the nozzle of the cleaner facing upwardly and inclined with respect to the platform, a strip of surface covering resting against the nozzle opening, and means carried by the platform and effective to limit the extent of lateral shifting movement of the lower edge of the surface covering away from the nozzle.
11. In a device for displaying the action of a suction cleaner having a nozzle, a support in the form of a platform, means on the platform for supporting the suction cleaner in a position with the nozzle of the cleaner facing upwardly and inclined with respect to the platform, a strip of surface covering resting against the nozzle opening, and guide means positioned to engage opposite ends of the surface covering to prevent shifting movement of the surfaces covering longitudinally of the nozzle and having provision for limiting the extent of shifting movement of the surface covering in a direction away from the nozzle.
12. In a suction cleaner display device, a suction cleaner having a nozzle and having driving mechanism, a support in the form of a platform, means on the platform for supporting the suction cleaner in a position with the nozzle opening facing upwardly and inclined with respect to the platform, for a strip of surface covering resting against the nozzle opening and having an area sufficient to cover the nozzle opening, suction means embodied in the cleaner and driven by the driving mechanism to draw the strip of surface covering against the nozzle opening, means in the nozzle and driven by the driving means to impart a vibratory movement to the strip of surface covering, a receptacle carried by the platform in a position to receive the foreign matter discharged from the surface covering by the vibratory movement thereof, and guide means adjustably mounted on the receptacle and engageable with the opposite ends of the surface covering to prevent shifting movement of the surface covering relative to the nozzle in a direction longitudinally of the nozzle.

ARTHUR L. McCARTHY.
